UNITED STATES PATENT OFFICE.

WILLIAM F. NORMAN AND JOHN H. BERGHAUSER, OF NEVADA, MISSOURI.

METALLIC ROOF-CRESTING.

SPECIFICATION forming part of Letters Patent No. 700,364, dated May 20, 1902.

Application filed January 2, 1902. Serial No. 88,206. (No model.)

To all whom it may concern:

Be it known that we, WILLIAM F. NORMAN and JOHN H. BERGHAUSER, citizens of the United States, residing at Nevada, in the 5 county of Vernon and State of Missouri, have invented a new and useful Metallic Roof-Cresting, of which the following is a specification.

This invention relates to metallic roof-crestings.

The object is in a simple, thoroughly effective, and ready manner and without the employment of solder, rivets, or like fastening devices to assemble the crest to the ridge-roll.

15 A further object is to present a cheap, highly-efficient, and durable form of metallic roof-cresting which may be readily manufactured and in which the cost of production will not be in excess of those forms of cresting in use in which the crest is associated with the ridge-roll by rivets, solder, or the like.

With these and other objects in view, as will appear as the nature of the invention is 25 better understood, the same consists in the novel construction and combination of parts of a metallic roof-cresting, as will be herein-after fully described and claimed.

In the accompanying drawings, forming a 30 part of this specification, and in which like numerals of reference indicate corresponding parts, there is illustrated a form of embodiment of the invention capable of carrying the same into practical operation, it being understood 35 that the elements therein exhibited may be varied or changed as to shape, proportion, and exact manner of assemblage without departing from the scope of the invention, and in these drawings—

40 Figure 1 is a view in perspective of a roof-cresting characterizing this invention. Fig. 2 is a similar view showing the parts of the cresting detached. Fig. 3 is a view in end elevation, showing the manner in which the 45 crest is associated with the ridge-roll. Fig. 4 is a view showing a slightly-modified manner of assembling the crest with the ridge-roll.

Referring to the drawings, 1 designates the 50 ridge-roll, and 2 the crest. Each of these parts may be of any ornamental design pre-

ferred, that herein shown being one of many that may be employed.

The ridge-roll herein shown comprises two legs or sides 3, which are designed to extend 55 over the comb of the roof, and to be secured there in any suitable manner, two outward-curved shoulders 4, and a downward-disposed gutter or hollow flange 5, within which the lower edge of the crest 2 is secured, as shown 60 in Fig. 3. The ridge-roll is made of a single piece of suitable metal and has each end provided with an incut 6 to permit connection with an adjacent cresting, thus to form a continuous structure along the comb of the roof. 65

The crest 2 may be made of the same metal as the ridge-roll or of different metal and has its lower edge reduced in width to correspond to the width of the gutter, as shown at 7, the metal above the reduced portion extending 70 out flush with the ends of the ridge-roll, as clearly shown in Fig. 1. The lower end of the crest is placed within the gutter, and then by subjecting the gutter to the action of a pair of crimping or seaming rollers the gutter and with it the portion of the crest within 75 it are closely pinched together and kinked or seamed, as at 8, thereby firmly securing the crest to the ridge-roll against possibility of accidental separation and avoiding the necessity of solder, rivets, or other adjunctive fastening devices for the purpose. The assembling of the crest with the ridge-roll may be readily and quickly effected, resulting not only in a saving in time in the production of 80 the finished article, but presenting a structure that will be strong, durable, and of neat and finished appearance. In order to reinforce the crest against tendency to bending or flexure, as from wind-pressure, the same 85 may be corrugated longitudinally of its length, as at 9, thereby not only serving the function stated, but also giving an ornamental appearance to the structure as a whole.

Instead of having the gutter 5 disposed below the plane of the top of the ridge-roll, as shown in Figs. 1, 2, and 3, the same may be arranged above the same, as shown in Fig. 4, and when the gutter is so positioned the lower end of the crest is secured therein in 95 the same manner as that already described.

Having thus fully described our invention,

what we claim as new, and desire to secure by Letters Patent, is—

- 5 1. A ridge-roll provided with a hollow flange or gutter, in combination with a crest interlocked with the walls of the flange.
- 10 2. A ridge-roll provided with a longitudinally-disposed gutter terminating short of the ends thereof, and a crest having its lower portion interlocked with the walls of the gutter.
- 15 3. A ridge-roll provided in its top with a downward-extending gutter, in combination with a crest having its lower edge reduced in length and interlocked with the walls of the gutter.
- 15 4. A ridge-roll provided with a longitudinally-disposed gutter terminating short of the ends thereof, and a crest having its lower edge

reduced in length to correspond with that of the gutter and interlocked therewith.

- 5 20 5. A ridge-roll provided with a longitudinally-disposed gutter terminating short of the ends thereof, and a transversely-corrugated crest having its lower edge reduced in length to correspond with that of the gutter and interlocked therewith.

25 In testimony that we claim the foregoing as our own we have hereto affixed our signatures in the presence of two witnesses.

WILLIAM F. NORMAN.
JOHN H. BERGHAUSER.
